UNITED STATES PATENT OFFICE

2,003,874

CORN SHOCK HOLDING AND BINDING DEVICE

Ernest L. Bailey, Boscawen, N. H.

Refiled for abandoned application Serial No. 530,396, April 15, 1931. This application October 3, 1934, Serial No. 746,732

1 Claim. (Cl. 100—31)

This invention relates to an especially designed holding device somewhat in the nature of jaw equipped tongs expressly constructed to function as a binding and retaining device for a shock of 5 grain, for example rough stalk corn.

Briefly stated, the preferred embodiment of the invention is characterized by a pair of companion members pivotally connected together and formed with arcuate gripping jaws and supplemental actuating handles, and latch retaining means for holding the jaws in relative set position.

One feature of the invention is predicated upon the simple and economical construction of the 15 jaw and handle equipped members which may be fashioned from sturdy metal rods of a readily accessible type.

A further feature of the invention is founded on the use of a pivoted latch and keeper pin 20 for selective cooperation with the latch, the latch and pins being so arranged as to permit the latch to bridge the pivotal joint between the respective companion jaw members.

Other features and advantages will become 25 more readily apparent from the following description and drawings.

In the drawings:

Figure 1 is a top plan view of the complete appliance as constructed in accordance with the 30 present invention.

Figure 2 is a side elevational view thereof.

Figure 3 is a cross section on the line 3—3 of Figure 1.

Figure 4 is a plan view with the jaws released 35 and swung to open position.

Figures 5 and 6 are detail sections on the line 5—5 and 6—6 respectively of Figure 1.

The entire assembly may well be seen in Figure 4, wherein it will be observed that the companion 40 members are distinguished by the numerals 7 and 8 respectively. As before stated, these members are formed from a single length of rod of appropriate measurements to fulfill the required results.

Each member is bent upon itself to form a 45 handle and a jaw. The member 7 is provided with a substantially arcuate or semi-circular shock-embracing jaw 9 and a laterally directed handle 10. Likewise the member 8 is formed with a correspondingly shaped jaw 11 and a laterally bent handle 12.

The points where the handles join the jaws form a convenient place for connecting the members 7 and 8 together, and this is accomplished 50 by a pivotal connection generally represented at 13. Pivoted to the jaw 9 near this pivot 13 is a latch 14 having a retaining hook 15 at its free

end. This hook is designed for selective engagement with keeper pins 16 mounted on the jaw 11 near the same pivot 13.

This jaw 11 is also provided with integral C-shaped cord guides 17 mounted at longitudinally spaced points as shown in Figures 1 and 2. The particular formation of each guide is illustrated better in Figure 3.

These guides are designed to accommodate the free end portion of a tying cord or bundling wire 18. The inner end of this cord is wound on a spool 19 here shown as of conical form, said spool being mounted for rotation on a spindle pin 20 carried by the jaw 11. This arrangement allows the cord to be threaded through the guides and renders the free end accessible to be drawn around the bundle of grain for tying after it is compressed and bound by the action of the clamping jaws 8 and 9.

The operation of the device is simple. By placing the device in open position as illustrated in Figure 4 and gathering the stalks of the corn shocks in the usual way, the jaws may be conveniently placed around the shock to bind the stalks together into tight compressed relationship. This 25 clamping and binding action is maintained through the medium of the latch 14, its hook 15 selectively engageable with the keeper pin 16.

After securing the desired compressed state in the bundle or shock, it is tied, as before implied, 30 the convenience of having the cord and spool and guide mounted directly on this clamp structure is a highly satisfactory arrangement.

It is thought that the description taken in connection with the drawings will enable a clear 35 understanding of the invention to be had. Therefore, a more lengthy description is thought unnecessary.

While the preferred embodiment of the invention has been shown and described, it is to be 40 understood that minor changes in shape, size, material and arrangement of parts coming within the field of invention claimed may be resorted to in actual practice if desired.

I claim:

In a hand grain shock binding and stalk retaining implement comprising a clamp including a pair of companion jaws, said jaws being of general semi-circular configuration and pivotally connected at one end, actuating handles formed 50 integral with the pivoted ends of said jaw, a latch pivotally carried by one of the jaws adjacent the pivotal connection of the jaws and latch engaging means carried by the other jaw adjacent the pivotal connection.

ERNEST L. BAILEY.
